UNITED STATES PATENT OFFICE.

LESTER A. CHERRY, OF KENMORE, NEW YORK.

COMBINED DAMPER-REGULATOR, RELIEF-VALVE, GAGE, AND ALARM.

1,148,755.

Specification of Letters Patent.

Patented Aug. 3, 1915.

Application filed August 27, 1914. Serial No. 858,965.

To all whom it may concern:

Be it known that I, LESTER A. CHERRY, a citizen of the United States, residing at Kenmore, in the county of Erie and State of New York, have invented a new and useful Combined Damper-Regulator, Relief-Valve, Gage, and Alarm, of which the following is a specification.

My invention relates to improvements in damper-regulators for use in vapor heating-systems, the principal objects of the invention being to produce a damper-regulator that will be positive and accurate in its operation of opening and closing the dampers of the heating apparatus in accordance with the pressure within the system, and which is of such comparatively simple construction and arrangement as to be capable of being cheaply and readily manufactured and applied and not at all likely to get impaired by use or out of working order.

Further objects of the invention are to so construct and arrange the regulator as to cause it to serve as a gage for the pressure, an alarm when the pressure passes a predetermined point, and as an efficient relief-valve that will positively blow-off at a predetermined pressure of vapor.

Other objects and advantages of the invention will hereinafter appear, and the novel features thereof will be particularly pointed out in the appended claims.

Referring to the drawings—Figure 1 is a plan view of a combined damper-regulator, gage, alarm, and relief-valve, constructed in accordance with my invention. Fig. 2 is a vertical sectional view of the same through the center. Fig. 3 is a front elevation of a fragment of the regulator showing the pressure-gage in front elevation. Fig. 4 is a similar view showing the pressure-gage in side elevation. Fig. 5 is an elevation of the upper portion of a round-type of boiler showing my invention attached to the dome thereof.

Similar numerals of reference indicate similar parts in all the figures of the drawings.

In carrying out my invention, I employ an annular chamber 1, the wall of which at or about its middle, tends inward, to form a reduced lower end 2. Rising from and preferably cast integral with the bottom of this chamber 1, is an annular flange 3, reduced

midway its ends, as at 4, thereby combining 55 with the wall 2, to produce an annular substantially U-shaped channel 5. The internal flange 3 is open at its upper end, which latter is considerably below the upper end of the chamber 1, and over said opening of the 60 flange is an inverted bell-shaped diaphragm 6, the annular wall of which is within the before-mentioned U-shaped annular channel 5 and upon whose bottom it rests. This diaphragm, therefore, is of substantially the 65 same depth as the internal annular flange 3, and serves to normally close the space enclosed by the same.

The upper end of the chamber 1 is closed by a cover 7, bolt 8, being employed for connecting said cover to the flange of the chamber. The cover 7 is provided with a central escape-opening 9.

The bell-shaped diaphragm 6 is provided with a central opening 10 in vertical alignment with the escape-opening 9 of the cover 7 and the bottom of the chamber is provided with a centrally located internally threaded depending boss 11, the outer surface of which may be formed polygonal or angular 80 to adapt it to receive a wrench. This boss, it will be understood, is by a pipe 12, connected to the steam-dome 13, of a boiler 14. (See Fig. 5.) A guide-bar 15, spans the depending boss 11, at its upper end, and is 85 held in position by bolts 16. This guide-bar is centrally perforated and receives the lower plain end of a rod 17, which extends upwardly through the opening 10 of the bell-shaped diaphragm 6 and cover 7, escape-opening 9 of the same, the latter opening being of considerably greater diameter than the rod 17. At a point above the guide-bar 15, the rod 17 is threaded, and to lend to its stability, it may also pass through 95 a brace 18, riveted at its ends to the underside of the bell-shaped diaphragm, from which it depends and having a perforation that receives said rod. Above and below the brace, nuts 19, may be mounted on the rod so 100 as to clamp the brace, and similar nuts 20, may also be threaded on the rod above and below the top of the diaphragm and, in addition to serving to hold the rod in proper relation to the diaphragm, also serve to 105 clamp upon washers 21, used to close the opening 10 in said diaphragm.

Located at the upper end of the rod 17,

- and locked in position by a jam-nut 22, is a yoke 23, between the bifurcations of which is located a lever 24, a transverse pin 25, serving to pivotally connect these two parts.
- 5 The opposite end of the lever 24, extends between the bifurcations of a slotted fulcrum-block 26, located on the perimeter of the chamber 1, being fulcrumed thereon by means of a transverse pin or pintle 27.
- 10 Pinned to about the center of the lever 24, is a slotted block 28, and within the same is located the damper-operating lever 29, somewhat longer than the lever 24, and adjustably connected to the latter by a set-screw 30. The damper operating lever 29 carries an adjustable weight 31, which may be secured in its adjusted positions by a set-screw 32, and at its front and rear ends said lever 29 is connected to damper-operating chains 33 and 34, respectively. The chain 33 leads to the usual draft-damper of the ash-pit of the furnace, while the chain 34 leads to the usual check-damper in the smoke-pipe. (See Fig. 5.) It will be understood, that in very large boilers, where the lever 29 would, therefore, have to be unreasonably long, the chain 34, instead of being connected to the rear end of the lever, as shown in Fig. 2, may be connected to the front end of said lever and then carried upward and rearward over suitable pulleys to a point where it could be dropped to and connected with the check-damper.
- 15 Communicating with and extending from the channel or well 5, of the chamber, and at the bottom thereof, is a pipe-connection 35, the bottom of the chamber, at this point, having a drain 36, normally closed by a screw-plug 37. The pipe 35 is of L-shape, and has an extension 38, extending forwardly therefrom and perforated, while seated and secured in its vertical portion, by means of a packing and nut 39, is a gage-glass 40, the upper end of which is open.
- 20 Immediately above the extension 38 of the pipe-connection 35, the cover 7 of the chamber is likewise extended, as at 41, and, like the extension 38, is perforated, ordinary guard-rods 42, depending through the same.
- 25 Upon the gage-glass and capable of vertical adjustment with relation thereto, is a substantially U-shaped but horizontally disposed gage-plate 43, the terminals of this plate being perforated to loosely receive the rods 42. An adjusting-screw 44, is threaded in a suitable opening formed in the lower extension 38, and is disposed upwardly and supports the gage-plate 43, whereby, the latter may be supported in any of its adjusted positions.
- 30 Immediately above the upper open end of the gage-glass is an electrical connection 45, from which leads a circuit-wire 46, the latter being in electrical circuit with a suitable battery and buzzer or other style of alarm. The battery and alarm are

of the conventional style and are herein shown. The remaining battery terminal 47, may be connected at any convenient point of the apparatus, as for instance, at the bottom of the plug 37.

35 This completes the construction of the apparatus, and the operation may be briefly described as follows: The U-shaped channel or well 5 is partially filled with a body of mercury, and when there is no pressure in the boiler, the parts occupy the position in which they are shown in Fig. 2, the height of the body of mercury being indicated by the lower dotted line. As the pressure of steam increases, it tends to lift the diaphragm, from the annular flange 3 so that said diaphragm moves vertically, being guided in its movements by the perforated guide-plate 15, and the wall of the chamber and the annular vertical flange 3, (the two combining to form the reduced channel,) the slotted fulcrum-block 26, and the fulcrum pin 27, such vertical movement of the diaphragm being against the weight 31. By means of these connections and the guide 35 the depending wall of the diaphragm is always maintained within the channel or well 5. The weight 31 is, of course, adjusted in accordance with the degree of pressure at which the system is to be operated. This 40 upward movement of the diaphragm, causes a downward movement of the front end of the lever 29, and the chain 33, at that end of the lever lowers and either partially or wholly closes the damper at the ash-pit of the furnace, thus cutting off or decreasing the supply of air to the fuel accordingly. By this same operation, the rear end of the lever 29 is elevated, and, through the chain 34, lifts the check-damper in the smoke-pipe, 45 thus still further reducing the rate of combustion by a reduction of draft. In this manner the operation of these two drafts serves to control the fire. In the event the pressure, for some reason, should not be 50 controlled by the manipulation of these dampers, and continues to rise until it reaches a given point, the latter being determined by the design of the chamber and the quantity of mercury employed, said 55 pressure, acting on the body of mercury, will force the latter down until that portion of its surface, within the diaphragm, more nearly approaches the bottom of the chamber. When this occurs, the diaphragm will 60 have reached its highest point of elevation. Further increase in pressure will now cause the steam within the diaphragm to force the mercury below the lower edge of the diaphragm and thus escape thereunder up 65 through the body of mercury within the channel 5 and outside of the diaphragm and from thence out through the escape-opening 70 after which, the pressure having lowered, the mercury will return to the position 75

shown by dotted lines in Fig. 2. This affords a positive relief from any excess pressure and removes all danger.

Of course the pressure of steam within the diaphragm will cause the mercury in the gage-glass to rise correspondingly, so that the actual pressure of the boiler may be read thereon at any time. The adjustable scale behind the gage-glass is preferably graduated so as to show or indicate this pressure in ounces per square inch. When no pressure is on, the scale is adjusted up or down until the zero of the scale is in alinement with the body of mercury in the gage-glass, the adjusting screw 44 being used for this purpose, the same being locked by means of a lock-nut 48. Any change in pressure may then be readily read from the scale. Suitably insulated, and extending downwardly from the electrical connection 45, within the upper open end of the gage-glass, is a platinum wire or electrode 49, vertically adjustable by means of a milled nut 50, to and from the column of mercury within the glass. This electrode is, of course, adjusted at the proper height above the column of mercury, so that when the latter rises, said column and the electrode contact and complete the electric circuit and the buzzer, before mentioned, or other style of alarm-device is sounded.

From the foregoing description, it will be apparent that I have produced a most efficient and dependable draft-regulator, the construction being such as to render it capable of also serving as a safety-device and as an alarm.

It will be understood that I have herein merely described and illustrated the preferred form of construction, and that the same may be altered as to details without departing from the spirit or sacrificing the advantages of my invention.

Having described my invention, what I claim, is:

1. The combination with a steam-boiler, of a damper-regulator, the same comprising an annular chamber, having an escape-opening at its upper end and connected to the boiler, and having a vertically disposed internal annular flange of less depth than and combining with the wall of the chamber to form a shallow annular channel adapted to receive a body of mercury, an inverted bell-shaped diaphragm mounted over the internal flange, approximating the same in depth and having its side-wall depending into said channel, a rod extending upwardly

from the diaphragm and through and above the opening in the chamber, a lever fulcrumed upon the chamber and connected to the rod, and connecting chains between the lever and the dampers of the boiler.

2. The combination with a steam boiler, of a damper regulator, the same comprising an annular chamber, reduced at its lower end, at its bottom connected to the boiler, and having an internal hollow flange outwardly flared at its bottom and combining with the wall of the chamber to form an annular reduced guide-channel adapted to receive a body of mercury, an inverted bell-shaped diaphragm mounted over the internal flange and approximating the same in depth and having its side-wall depending into said reduced guide-channel, a rod extending upwardly from the diaphragm and above the chamber, a lever fulcrumed on the chamber, an extension adjustably connected therewith, a weight adjustable on the extension, and chains leading from the extension to the dampers of the boiler.

3. The combination with a steam-boiler, of a damper regulator connected therewith, the same consisting of an annular closed chamber having a central escape-opening in its top and an inlet-opening in the bottom connected to the boiler, an internal annular flange rising from the bottom of less depth than the chamber and combining therewith to form an annular channel, a body of mercury therein, an inverted bell-shaped diaphragm approximating in depth that of the annular flange and arranged over the same and having its side-wall depending into the channel, a perforated stay or brace depending from the underside of said diaphragm, a perforated guide over the inlet-opening in the bottom of the chamber, a rod extending through, above and below the top of the diaphragm and the stay or brace and through the guide, clamping-nuts on the rod above and below the diaphragm and the stay or brace, a weighted lever above the chamber, a pivotal connection between the same and the upper end of the rod, and chains leading from the weighted lever to the dampers of the boiler.

In testimony whereof I have signed my name to this specification in the presence of two subscribing witnesses.

LESTER A. CHERRY.
